Andrew Little INVENTOR

BY A. Sidney Doane

ATTORNEY

UNITED STATES PATENT OFFICE.

ANDREW LITTLE, OF NEW YORK, N. Y.

DESIGN FOR A FONT OF PRINTING-TYPE.

SPECIFICATION forming part of Design No. 12,890, dated April 18, 1882.

Application filed March 9, 1882. Term of patent 7 years.

To all whom it may concern:

Be it known that I, ANDREW LITTLE, of the city, county, and State of New York, have invented and produced a new and original 5 Design for a Font of Printing-Type, of which the following is a specification.

The nature of my design is clearly shown in the accompanying typographic impression, to which reference is made; and it consists of an 10 ornamented letter the up and down portions of which are inclined inward at the top and bottom to a central point, at which they meet, and the faces of the letters ornamented by the 15 heavy figures following the configuration of the outline. The letters are also ornamented

by a light vertical line extending above and below them, which is provided with the heavy spear-head-like ornaments shaded upon the right, and the light ring-like figures, as shown.

In the lower-case, figures, and symbols the 20 character of the design is preserved; but the light vertical line described as characterizing the capital letters is omitted.

I claim as new—

The design for a font of printing-type, as 25 shown and described.

ANDREW LITTLE.

In presence of—

THOS. B. BARNES,
WILLIAM V. H. HICKS.
